SCREEN FOR PAINT GUNS

John D. Yarnell, Seattle, Wash.

Application August 22, 1945, Serial No. 612,062.

2 Claims. (Cl. 210—170)

1

This invention relates to screens for paint guns, and particularly to screens for suction tubes when extended obliquely through the receptacles containing the material to be sprayed.

In the operation of spraying paints and lacquers, a gun or spraying device is ordinarily used with a very small nozzle connected with a suction tube extended down through a cover on the receptacle in an oblique direction to a lower corner of the receptacle to suck up all of the material, when the receptacle is to be tipped to one side. In order to prevent any clogging of the nozzle it is important that the materials be screened before entering the mouth of the tube.

It is important for free flow of paint that the screen be supported in spaced relation from the mouth of the nozzle and in spaced relation from the walls and bottom of the receptacle, and that it provide a surplus quantity of screened material at all times available to be drawn upward by the tube.

Any screen used, must be supported by the tube, and difficulty is found in attaching a suitable screen to the oblique portion of the tube, to extend beneath the mouth thereof, and still permit the turning of the tube within the receptacle when the cover to which it is attached, is screwed down upon the ordinary threads on the top of the receptacle, for air tight seal.

It is also important that the top of the screen device be relatively small to prevent the paint and material from settling and congealing thereon.

It is therefore an object of this invention to provide a screen in the general form of a cone, which may be adjustably connected to the oblique portion of the tube, by a resilient collar at the top of the cone. It is another object to provide the sides of the cone of different lengths, so that the longer side may be supported over the oblique wall of the tube, and the shorter side stand in extended relation therefrom, and in spaced relation above the bottom of the receptacle, and free to swing above the base of the receptacle when the tube is connected to the receptacle by the turning and threading of the cap thereon.

It is a further object to provide a simple and efficient method, for laying out and forming the parts of the cone, and for connecting the parts to each other, and for connecting the cone to the tube.

With these and other objects to be hereinafter stated, I have illustratively exemplified my invention by the accompanying drawing, of which:

Figure 1 is a front elevational view with parts broken away and with parts in section of a paint receptacle, a suction tube therein having an oblique portion, and a conical strainer of my invention on said oblique portion;

2

Fig. 2 is an enlarged fragmentary elevational view with parts in section of said suction tube with my conical strainer thereon;

Fig. 3 is an enlarged sectional view taken substantially on broken line 3—3 of Fig. 1;

Fig. 4 is a plan view of a blank which may be employed in providing the completed strainer of the other figures; and

Fig. 5 is a fragmentary sectional view showing a manner of securing together the sides and bottom of my strainer.

Like characters on the different figures represent like parts.

The letter A indicates any ordinary pot or receptacle in which any supply of paint or lacquer may be provided on removal of the cover B, which is threaded upon the neck of the pot. A suction tube C is attached through the cover and is provided on its top with a spraying nozzle D. A handle E with an ordinary trigger F and an air connection tube G enables the operator to use the gun in the ordinary manner.

The tube C is ordinarily bent at some point below the cover, in an oblique direction shown as portion 6 and extended to near one outer edge of the bottom 7 of the pot for draining approximately all of the paint therefrom when the pot is tipped toward one side for that purpose by the operator. In order to prevent the nozzle from clogging from any particles as congealed paint and lacquer, and to assure a uniform flow of the paint or lacquer from the nozzle a special form of fine mesh screen is provided.

This screen is in the general form of a cone with perforated walls in spaced relation from the tube 6 and in spaced relation below the lower end 9 or mouth of the tube, to provide a relatively large enclosure for screened material into the mouth of the tube. The top, apex or vertex of the cone has an open neck 10 for disposition upon the angular portion of the tube and the edges of the screen are folded or rolled inward and downward to provide a resilient collar 11 which permits the neck to be pressed up over the tube to a desired position; but when released from manual pressure the collar grips the tube and sustains the screen in the desired position.

One side or portion 12 of the cone is supported partly by resting over the angular portion 6 of the tube, and the opposite side or wall 13 is disposed on a lesser slope and approximately in a perpendicular line between the neck 10 and the rim 14 of the bottom 15 of the cone which bottom is in spaced relation above the bottom of the pot, to permit free flow of the paint material through the sides and bottom of the cone in the chamber within the same for free flow into and from the suction tube. This formation of the conical screen is important because it must be

adjusted over the tube while both are outside of the pot, and if the wall at 13, or side, was as long as the opposite portion 12 it would strike the bottom of the pot 7 when the cover B was being screwed upon the top of the pot; because the sloping portion 6 of the tube would swing the bottom 15 of the cone below the fixed base or bottom of the pot, and thus crush or cause the neck or collar at the top of the cone to be dislocated from the desired position on the tube.

Fig. 4 shows a preferred form or blank of a piece of netting or screen which may be folded or formed into the cone shown in the other figures. The portion 11 of the completed screen is formed by the portion designated as 11 in Fig. 4 which is defined by the upper edge and the parallel edge indicated by a dot and dash line. The portions 16, which are folded back on each other in Fig. 3, are indicated by portions 16 in Fig. 4 and are bounded by the lateral edges and the dot and dash lines shown. The portions 17 which lie adjacent the edges of the bottom 15, as indicated in Figs. 2 and 5, are designated as 17 in Fig. 4 and are defined by the bottom edge of the blank and the parallel dot and dash line.

In forming the conical strainer of my invention, the portions 16 are turned in opposite directions and then the blank is rolled and the portions 16 are caused to hook together to maintain the conical form. Next the portion 11 is bent downwardly and inwardly to provide a tapered sleeve like portion so that the same will resiliently engage the tubular portion 6 and provide for adjustable holding of the screen by said tubular portion. Thereafter, the portion 17 is bent outwardly. Next the rim 14, which is circular as indicated in Fig. 3, is placed so that the portion 17 and the edges of the bottom 15 are within the rim 14. Then the rim 14 has its flanges pressed together to rigidly secure the bottom 15 to the conical screen. The portions 16 not only function to hold the lateral edges of the screen together but function as a stiffening member for the final screen.

A plane intersecting a cone at an angle to the normal base of a cone will provide an ellipse as is indicated by the elliptical shape 18 shown in Fig. 3. As it is desired to have a round bottom and a round ring 14, the side walls of the screen are bent and a slight hump 19 will appear.

It is desirable that the portions 16 be provided and that they not be soldered together so that the entire surface area, with the exception of the ring 14, may function as a strainer. Also grooves 20 are preferably provided and they function as stiffening members.

While I have shown the bottom 15 substantially at right angles to the wall 13 of the cone, it is to be expressly understood that this is not a limitation but is an illustration of a construction best suited to a device or paint pot having a bottom wall which is at right angles to the side walls. Obviously if a paint pot has a convex bottom, the angle of the bottom 15 to the side wall 13 can be changed to fit such shape of bottom. Such convex bottoms are not uncommon in fruit jars which are commonly employed as paint pots where paint is to be sprayed.

Obviously changes may be made in the forms, dimensions, and arrangements of the parts of my invention, the above setting forth only a preferred form of embodiment.

Having described my invention, I claim as new;

1. A screen for obliquely disposed suction tubes for spraying paint and lacquer liquids from a receptacle, comprising a relatively fine meshed flexible sieve having substantially a conical configuration in outline to prevent the liquid congealing on the top thereof when the supply is lowered, and to screen the material to be sprayed, the apex of the cone being provided with an aperture for entrance of the tube, the edges of the aperture being rolled down and inward for a collar for adjustably retaining the screen upon the tube, one side portion of the cone adjustably disposed upon and along the upper wall of the oblique portion of the tube for support, and the other side portion of the cone being shorter, to permit the cone to be turned around by the tube within the receptacle and above the base thereof when the tube is revolved for attachment to the receptacle top, a bottom sieve attached across the lower edges of the cone walls in spaced relation below the mouth of the tube and above the floor of the receptacle to provide free passage of the liquid from the receptacle through the meshes of the sides and bottom of the cone, the outer edges of the bottom of the cone and the lower edges of the sides thereof being crimped together for attachment and rigidity, and the sides having grooves pressed therein for further rigidity of the cone, while suspended in the receptacle for spraying.

2. In an apparatus for spraying liquid paints and lacquers, including a suction tube projected downward from the center of a cover for a receptacle for the liquid, and having its lower portion, bent obliquely toward the lower convergence of the walls and bottom of the receptacle, for emptying the same, in combination with, a conical screen for preventing paint particles from clogging the nozzle of the tube, the cone being provided with an opening and collar at its apex for adjustable connection with the tube, a screen across the bottom for enclosing the base of the cone, one side of the cone being adapted for lying along the upper wall of the oblique portion of the tube for support, and the other side of the cone being shorter, to permit the cone to be turned around within the receptacle together with the tube and above the bottom of the receptacle, and to support the bottom of the cone in spaced relation above the bottom of the receptacle, for free circulation of the liquid around and beneath the screen and for passage of the liquid through the meshes thereof.

JOHN D. YARNELL.
